UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

WARPER.

Application filed May 12, 1921. Serial No. 468,897.

To all whom it may concern:

Be it known that I, ALONZO E. RHOADES, a citizen of the United States, residing at Hopedale, county of Worcester, State of

5 Massachusetts, have invented an Improvement in Warpers, of which the following description, in connection with the accompanying drawings, is a specification, like characters on the drawings representing like 10 parts.

This invention relates to a warper or machine in which a sheet of warps drawn from the spools or creel are wound upon a beam such as is used for the warp supply

15 in a loom.

It has been the practice to some extent to dye the warps after they are wound upon the beam, a process which is known as "beam dyeing", and improvements which 20 have been made in this method of dyeing have led to a larger use of the method. In beam dyeing, in order that the dye may penetrate evenly and thoroughly the mass of warp on the beam, it is necessary to control the tension of the warp wound on the

25 beam and the density of the wound warp mass. These features of tension and density chiefly determine the degree of permeability of the warp on the beam to the dye. If 30 the warp beam rests upon the driving roll of the warper, the pressure is a function of the weight of the warp beam and warp mass, and as the latter increases from nothing to a very considerable amount, this pressure varies within a wide range and materially affects the density of the warp mass. This variation in pressure, together with the retarding motion of the creel and of the 35 warper elements acting on the warp before it reaches the warp beam, also affect the tension of the warp as it is wound upon the beam.

It is the object of the present invention to provide a warper in which the tension 40 of the warp wound on the beam and the density of the wound warp mass are controlled as desired and particularly so as to secure the required permeability of the mass to the dye.

45 It is the object of the invention further to provide a construction in which the pres-

sure between the driving roll and the warp mass being wound on the warp beam may remain substantially constant and of a required degree during the entire winding operation.

55 It is the object of the invention further to provide a construction in which the warp beam rotates in fixed relation to the frame of the warper and in which the driving roll is yieldingly pressed into driving contact with the warp mass.

60 The object of the invention is further to provide improved means for controlling the tension of the warp as it is delivered to the beam.

65 The object of the invention is further to provide an improved construction for holding the warp beam in position and for controlling the movement of the warp beam into and from its position on the frame.

70 These and other objects and features of the invention will appear more fully from the accompanying description and drawings and will be particularly pointed out in the 75 claims.

In the drawings:

75 Figure 1 is a side elevation of a warper of a generally familiar type embodying a preferred form of the present invention.

80 Figure 2 is a rear elevation partially broken away of the construction shown in Figure 1.

85 Figure 3 is a side elevation looking toward the right of Figure 2 of the carriage for the driving roll and connected parts.

90 Figure 4 is a side elevation looking toward the left of Figure 2 of the inside of a portion of the left hand side frame.

95 The general type of warper which this invention is shown as embodied in is well known and familiar. It comprises the side frames 1 and 2 which rest upon the floor and are rigidly connected transversely by suitable girts, rods and shafts. A main girt 3 is shown extending between the side frames at the rear and bolted thereto at 4. A connecting rod 5 is also shown at the bottom, extending between the sides of the frame, and the sides are connected at other 100 points in addition.

The sheet of warp 6 comes from the usual

creel, passes over an idler roll 7 journaled at the top of the frame, down around a measuring roll 8, up over a second idler roll 9 journaled at the top of the frame, through drop wires 10 and over a third idler roll 11, journaled in a bracket 12 at the front of the frame, to the warp beam upon which it is wound.

- It is usual to rotate the warp beam to 10 effect the winding of the warp thereon by means of a beam driving roll having peripheral contact with the warp as it is wound on the warp beam. Thus the speed with which the warp is wound may readily be controlled or maintained constant as desired, notwithstanding the constant variation in the diameter of the warp mass.

An important feature of the present invention resides in providing a construction 20 in which the warp beam has fixed bearings in the frame, while the beam driving roll is mounted to have bodily movement toward and from the warp beam and is preferably yieldingly maintained with the requisite driving pressure in contact with the warp being wound on the warp beam.

In the preferred construction illustrated the warp beam 13 is provided at each end with the disks or heads 14 and with the axial 30 shaft or spindle 15. The sides of the frame are provided with alined curved seats 16. Cylindrical journal bearings 17 are placed over the ends of the spindle 15 on the warp beam and rest in the seats 16. These bearings, and consequently the beam, are held in position by suitable means such as the beam lock of novel construction provided.

The beam lock illustrated comprises a cap member 18 and a hook member 19. The cap member 18 is pivoted to the frame at 20, extends over the bearing 17 and is pivoted to the hook member 19 at 21. The hook member, when in position, hooks beneath a lug 22 projecting from the frame. The cap member 18 has threaded therein a set screw 23 abutting the bearing 17. It will thus be seen that when the warp beam is in position, as shown in Figure 1, and the set screw 23 is screwed down, the bearing 17 will be locked in rigid position on the beam. When it is desired to remove the warp beam the set screw 23 is turned to release the hook 19, the hook 19 is swung upwardly and the cap member 18 if necessary also, and the warp beam with the bearing 17 is removed.

The frame at each side is provided with a forwardly extending bracket 24 curved on its upper surface 25 to form a track merging with the seats 16. This bracket 24 is pivoted upon a vertical pivot 26 to the frame so that it may be swung back against the frame. These brackets 24 with the cylindrical bearings 17 afford a simple and practical means for positioning the warp beam on and removing it from the warper.

The warp beam may be pulled on a truck in front of the warper, the bearings 17 slipped over the spindle 15 and then the warp beam rolled up on the tracks 25 into its seat. After the warp beam is filled and ready for removal a truck may be drawn up in front of the warper, the beam locks released, and the warp beam with the bearings 17 rolled down the tracks 25 on to the truck. The brackets 24 being pivoted, are swung aside 75 when the warp beam is removed so that they will not be caught and broken and will not be in the way.

The beam driving roll in this invention is mounted for movement toward and from the warp beam and is yieldingly pressed into driving contact with the warp mass. As a preferred construction for securing this result, the driving roll is journaled in a carriage extending between the sides of the warp frame and mounted for a sliding movement in the frame, and preferably in a direction radially of the seats 16.

This carriage, one end of which is shown in Figure 3, comprises side plates 27 rigidly connected by a cross girt 28 bolted thereto at 29. The side plates 27 extend upwardly to form the angular projections 30 and on the exterior faces of the side plates are projections forming guides 31 which fit and slide in the track grooves 32 formed on the interior faces of the frame sides 1 and 2.

This carriage, with the beam driving roll and connected parts, is quite a heavy structure and tends normally to slide down in the 100 tracks 32 or away from the warp beam. Its weight is overcome and its yielding movement upwardly to bring the driving roll into driving contact with the warp on the warp beam is effected in any desired manner. 105 A simple and practical means for this purpose is illustrated.

The brackets 33 project rearwardly from the side frames of the warper and in these brackets is journaled a shaft 34 extending transversely of the warper. This shaft carries, rigidly connected thereto, a plurality of large pulleys 35 and a plurality of small pulleys 36. Suitable flexible connectors such as chains 37 are connected as at 38 to the carriage and extend over idler pulleys 39 journaled in the frame and are fastened to the small pulleys 36. Other chains 40 are fastened to the pulleys 35 and extend thereabout to weights 41 hanging at the rear. 110 These weights, which may be varied in number and size as required, together with the connectors described, not only serve to counterbalance the carriage and connected parts, but are arranged yieldingly to force the carriage with the driving roll into driving contact with the warp mass on the warp beam and to give the desired driving pressure. It will be seen that not only may this pressure be varied as required, but by rea- 115 120 125 130

son of the principle employed, this pressure remains substantially constant during the entire winding operation and regardless of the constant variation in diameter of the 5 wound warp mass.

The shaft 34 may be turned by hand in order to raise and lower the carriage whenever desired. For this purpose the shaft 34 is shown as provided at one end with a gear 10 42 meshing with a small pinion 43 on a shaft 44 from which projects or over which may be slipped a crank handle 45. A detent 46 is pivoted to the frame at 47 and may be swung upwardly into engagement with the 15 gear 42 to hold it against rotation when the handle is released. This effects a ready means for use when the warp beam is to be removed. The operator seizing the handle 45, rotates the shaft 34 sufficiently to lower 20 the driving roll out of contact with the warp beam. The detent 46 is then swung into engagement with the gear 42 to hold the carriage thus depressed.

The beam driving roll 48 is deeply recessed at its ends and the bearings for this roll are in these recesses, so that the driving roll 48 may move up as close as possible toward the center of the warp beam, allowing the heads 14 to pass down beyond the 25 axis of the driving roll 48. In the construction illustrated this is secured by providing journal brackets 49 bolted at 50 to the ends of the carriage 27, and projecting upwardly and inwardly. At their inner upper ends 30 these brackets are provided with caps 51 forming with the bracket bearings for the 35 shaft 52 of the driving roll.

Suitable means are provided for transmitting rotary movement to the shaft 52 and 40 consequently to the beam driving roll 48, regardless of the position which the carriage may occupy and regardless of the movement of the carriage, for securing this result herein illustrated.

The main driving shaft of the warper 53 is shown extending between the side frames in the rear and near the bottom it carries the usual fast and loose pulleys 54 and 55. A counter shaft 56 is mounted above the main 50 shaft 53 and has a bearing at one end in the side frame 3, and at the other end in a bracket 57 projected forwardly from and bolted to the cross girt 3 at 58. Intermeshing gears 59 on the main shaft and 60 on the 55 counter shaft cause the latter to be rotated from the former. The counter shaft 56 has secured thereto inside the frame, a pinion 61 meshing with a gear 62 journalled on a stub shaft 63 in a link 64 pivoted to the shaft 56. 60 It will thus be seen that, whatever position the gear 62 may occupy with respect to the pinion 61, it will always remain in mesh therewith. A short shaft 65 is mounted in the carriage 27 and extends parallel with 65 the beam driving roll shaft 52. This shaft

65 has a bearing at its end in the bracket 49 and the cap 51 is extended rearwardly to form the cap for this bearing. At its outer end the shaft 65 has a bearing in a bracket 66 secured at 67 to the side plate 27 of the 70 carriage. At its outer end this shaft 65 has secured thereto a gear 68 meshing with the gear 62. A link 69 is pivoted at one end to the shaft 63 and at the other end to the shaft 65, so that whatever position the former may 75 take with respect to the latter the gears 62 and 68 will always be in mesh. The shaft 65 drives the beam driving roll 48 and for that purpose is provided with a pinion 70 at its inner end meshing with a gear 71 on the 80 shaft 52, both of these gears being well within the recess in the end of the beam driving roll.

It will thus be seen that as the carriage 27 rises and falls or moves toward and away 85 from the warp beam, the train of gears at all times remains in mesh causing the motion to be transmitted to the beam driving roll 48.

The tension of the warp is largely controlled by the peripheral speed of the roll 8 90 with respect to the peripheral speed of the warp mass as it is wound on the warp beam. This roll 8 is referred to as the measuring roll because it is commonly employed to measure the length of warp wound on to the 95 beam. By varying the peripheral speed of this roll 8 with respect to that of the warp mass on the warp beam, it is possible to give any desired tension to the warp. This invention therefore provides means for adjusting or varying the peripheral speed of the measuring roll 8 and a preferred form of means for that purpose is herein illustrated.

A pair of oppositely disposed parallel frustro-conical pulleys are mounted between 105 the measuring roll 8 and the shaft 56. The lower 72 of these pulleys is journaled in a frame 73 mounted to swing vertically on and about the shaft 74 which shaft is journaled at one end in a bracket 75 mounted on the cross girt 3 and at the other end in the side frame 1. The upper 76 of these pulleys is journaled on a shaft 77 carried at its ends in the side frames 1 and 2 and at its center in the plate 78. The plate 78 is carried at its upper end by a tie rod 79 connecting the sides of the warper and at its lower end is secured to the bracket 75. A belt 80 connects the two pulleys 72 and 76 and supports the former with its pivoted frame 73 110 115 and is thus maintained under proper driving tension.

The shaft 74 carries a sprocket wheel 81 which drives a sprocket chain 82 running over a sprocket wheel 83 on the shaft 84 125 of the measuring roll. The shaft 56, which it will be remembered is driven from the power shaft 53, carries a sprocket wheel 85 which drives a sprocket chain 86 which in turn runs over a sprocket wheel 87 and 130

therefore drives the shaft 77 and the cone pulley 76. The cone pulley 76 drives the cone pulley 72 through the belt 80 and the cone pulley 72 is provided with a pinion 88 meshing with the gear 89 secured to the shaft 74. It will thus be seen that through the medium of these connections the measuring roll 8 is rotated from the power shaft of the warper. The peripheral speed of the roll 8 will depend upon the position of the belt 80 on the cone pulleys. This position is controlled by a belt shipper. This belt shipper is shown as a bar or plate 90 threaded on to the threaded shaft 91 which is journaled at its ends in the bracket 75 and the side frame 1. The shipper 90 has a bifurcated forward end sliding on a rod 92 extending between the plate 78 and the side frame 1 and also has a rearwardly projecting end 93. It will thus be seen that as the shaft 91 is rotated in one direction or the other, the shipper 90 will move in one direction or the other lengthwise of the cone pulley and shift the belt, effecting the desired change in the peripheral speed of the measuring roll 8. Any suitable means may be provided for automatically or manually rotating the shaft 91. It is found in practice that a manual control is usually sufficient and for this purpose the end 94 of the shaft 91 is formed of polygonal shape to receive a suitable handle or wrench.

Thus is shown a simple and preferred construction embodying the invention and enabling the desired result herein set forth readily to be secured. By varying the weights 41 any desired amount of driving pressure may be secured between the driving roll 48 and the warp mass being wound upon the warp beam, and by rotating the shaft 94 any desired relation of the peripheral speed of the measuring roll 8 to the peripheral speed of the warp mass and consequently any desired degree of tension in the warp as it passes to the warp beam may be secured. Thus the density of the warp mass and the tension of the warp in the mass and consequently the permeability of the warp mass to the dye may readily be controlled to secure any desired conditions.

Having thus described my invention, what I claim as new and desire to secure by Letters Patent, is:

1. A warper comprising a frame, a warp beam having fixed bearings in the frame, a beam driving roll mounted on the frame for bodily movement toward and from the beam, means for maintaining driving contact between the driving roll and the warp mass on the beam during the winding operation and for controlling the pressure therebetween.

2. A warper comprising a frame, a warp beam having fixed bearings in the frame,

a beam driving roll mounted for sliding movement on the opposite sides of the frame toward and from the beam.

3. A warper comprising a frame, a warp beam having fixed bearings in the frame, a beam driving roll mounted on the frame for bodily movement toward and from the beam, means for yieldingly moving the driving roll into driving contact with the warp mass being wound on the beam and for maintaining constant during the winding operation the pressure exerted by the driving roll on the warp mass thereby to produce a uniform density in the warp mass.

4. A warper comprising the construction defined in claim 2, together with means for yieldingly sliding the driving roll into driving contact with the warp mass being wound on the beam.

5. A warper comprising a frame, a warp beam having fixed bearings in the frame, a carriage extending between the sides of the frame, a beam driving roll journaled in the carriage, guideways in the sides of the frame cooperating with and guiding the ends of the carriage to permit a bodily movement thereof toward and from the beam.

6. A warper comprising the construction defined in claim 5 in which the said guideways extend radially of the beam axis.

7. A warper comprising a frame, a warp beam having fixed bearings in the frame, a beam driving roll mounted for bodily movement in the frame toward and from the beam, and means for continuously rotating the driving roll and moving it bodily toward the warp beam to effect the winding of the warp onto the warp beam and for maintaining constant the pressure of the driving contact with the wound warp.

8. A warper comprising a frame, a warp beam having fixed bearings in the frame, a beam driving roll mounted for bodily movement in the frame toward and from the beam, a driven shaft in the frame, and movable driving connections between the driven shaft and the driving roll to effect the rotation of the driving roll as it moves bodily to maintain driving contact with the warp wound on the beam.

9. A warper comprising a frame, a warp beam having fixed bearings in the frame, a beam driving roll mounted for bodily movement in the frame toward and from the beam and means for maintaining the driving roll in driving contact with the warp mass wound on the beam as the driving roll is moved back by the increasing diameter of the mass.

10. A warper comprising a frame, a warp beam having fixed bearings in the frame, a carriage extending between the sides of the frame, a beam driving roll journaled in the carriage, means for guiding the carriage

on the frame to permit a bodily movement thereof toward and from the beam, idler pulleys journaled on the frame, a shaft extending transversely of the frame at the

5 rear, flexible connectors extending from the carriage over the idler pulleys to said shaft, and a weight connected to said shaft acting to counterbalance the carriage and rotate the shaft to force the driving roll into driving 60 contact with the warp being wound on the warp beam.

11. A warper comprising the construction defined in claim 10 together with means for manually rotating the said transverse shaft 15 to raise and lower the carriage.

12. A warper comprising a frame, a warp beam having fixed bearings in the frame, a beam driving roll mounted on the frame for bodily movement toward and from the 20 beam, means for yieldingly moving the driving roll into driving contact with the warp mass being wound on the beam, a measuring roll about which the warp passes on its way to the beam, a power shaft, means for 25 rotating the driving roll from the driven shaft during its bodily movement, means for driving the measuring roll from the driven shaft and means for varying the speed at which the measuring roll is driven 30 relatively to the speed of the driven shaft.

13. A warper having the construction defined in claim 12 in which the said means for varying the speed of the measuring roll includes a pair of oppositely disposed conical pulleys, a belt connecting the said pulleys and means for shifting the belt.

14. A warper comprising a frame, a warp beam having fixed bearings in the frame, a beam driving roll mounted on the frame for 40 bodily movement toward and from the beam, means for yieldingly moving the driving roll into driving contact with the warp mass being wound on the beam, a measuring roll about which the warp passes on its way 45 to the beam, means for positively rotating the measuring roll and means for adjusting the speed of rotation of the measuring roll with respect to the speed of rotation of the driving roll thereby to control the tension of 50 the warp as it is wound on the warp beam.

15. A warper comprising a frame, aligned curved seats formed thereon at the front thereof, forwardly projecting brackets curved on the upper surfaces to form tracks 55 merging with the seats upon which the warp

beam may be rolled into and out of position in the seats, the said brackets being pivotally mounted on the frame so as to be swung out of the way.

16. A warper having the construction defined in claim 15 together with cylindrical journal bearings for the warp beam and means for removably locking the said journal bearings in the said seats.

17. A warper comprising a frame having 65 a curved seat, a warp beam having a spindle, a cylindrical journal bearing for the spindle and fitting the said seat, a forwardly projecting bracket on the frame presenting a track merging into the said seat upon which 70 the journal bearing may be rolled into and out of the seat, and means for removably locking the journal bearing in the said seat.

18. A warper comprising the construction defined in claim 17 in which the said locking means comprises a lug on the beam, a cap member pivoted to the frame, a hook member pivoted to the cap member and adapted to hook beneath the lug, and a set screw mounted in one of said members and 80 abutting the journal bearing.

19. A warper comprising a frame, a warp beam, a beam driving roll contacting with the warp on the beam and acting therethrough to rotate the beam, and means for 85 maintaining during the winding operation a constant surface pressure between the driving roll and the warp mass on the beam thereby to secure a uniform density in the 90 warp mass.

20. A warper comprising the construction defined in claim 19, together with means for feeding the warp through the warper on its way to the beam and means for correlating the speed of rotation of the driving roll 95 with the speed of said feeding means to maintain a constant tension in the warp as it is wound on the beam.

21. A warper comprising the construction defined in claim 19, together with a measuring roll, means for driving the measuring roll to feed the warp through the warper on its way to the beam, and means to correlate the speed of rotation of the driving roll and the speed of rotation of the measuring roll to maintain a constant tension in the warp as it is wound on the beam.

In testimony whereof, I have signed my name to this specification.

ALONZO E. RHOADES.
